UNITED STATES PATENT OFFICE

ALBERT J. KOMENAK, OF STAMFORD, CONNECTICUT, ASSIGNOR TO THE EXCELSIOR HARDWARE COMPANY, OF STAMFORD, CONNECTICUT, A CORPORATION OF CONNECTICUT

TRUNK LOCK

Application filed September 6, 1928. Serial No. 304,946.

This invention relates to locks for trunks, chests, suit cases, and other similar articles, and the particular style of lock comprises a hook-shaped element carried by the lid of the trunk or other article, and a lock proper secured to the body of the trunk or other article and provided with a draw bar which is adapted to be engaged beneath said hook and then secured in this position by the operation of a suitable key.

The features of this invention are embodied in the very simple key operated means for locking and unlocking the parts, the particular aim of the invention being to provide a very simple and efficient lock of this description, which, notwithstanding its simplicity, cannot be operated except by the use of the usual corrugated key, thus adding to the security of the device.

A preferred embodiment of the invention is illustrated in the accompanying drawings which are to be read as a part of this specification, and in which

Figure 1 is a front elevation of the lock as it appears with the parts in locked condition.

Figure 2 is a side elevation of the structure shown at Figure 1.

Figure 3 is a view similar to Figure 2 but showing the relative positions of the parts of the lock carried respectively by the cover and body of the trunk or other article when the parts are disengaged from locking position.

Figure 4 is a section at the line 4—4 of Figure 1.

Figure 5 is a detail front view of the part of the lock carried by the body of the trunk or other article with the draw bar removed.

Figure 6 is a similar view with the draw bar and lock lever removed.

Figure 7 is a rear view of the construction shown at Figure 1.

Figure 8 is a detail broken view showing the interior of the lock with the parts in the position they assume when the trunk or other article is unlocked.

Figure 9 is a view similar to Figure 8, showing the position of the parts when in locked condition, and

Figure 10 is a detail elevation of the key. Similar numerals of reference denote like parts in the several figures of the drawing.

1 is an escutcheon secured to the lid of the trunk or other article and carrying at its lower edge a hook-shaped member 2, the opening of the hook being directed upwardly and the top of this member being formed into any convenient finger lift 3.

4 is an escutcheon plate secured to the body of the trunk or other article and having formed integral therewith near its upper edge a hollow raised portion 6 while to the inside of the escutcheon plate 4 is secured the casing 7 which contains and supports the locking mechanism.

Referring to Figures 8 and 9, 8 is a locking slide contained and guided within the casing 7 and having at its upper extremity flanges 9, 10, a spring 11 being confined between the flange 9 and the upper wall of the casing with its free or active end bearing against the flange 10, so that it will be clear that the function of this spring is to normally throw the slide 8 downwardly said spring yielding when this slide is forced upwardly.

12 is a tumbler pivoted at 13 to the slide 8 and normally extending athwart said slide, and having a gate 14 in its upper edge about midway of its length.

15 is a leaf spring that is secured to the tumbler 12 at its heel end below the pivotal point 13, the free end of this spring bearing against a lug 16 that is carried by the slide 8, the function of this spring being to normally throw the tumbler upwardly against the stop 17 carried by the slide.

The slide 8 has a leg 18 which abuts against the lower wall of the casing 7 in order to limit the downward throw of the slide owing to the action of the spring 11, and from the bottom central portion of the slide extends a lock bolt 19 to which access is had through an opening 20 in the face of the plate 4, for the purpose presently to be explained, a similar opening 21 being formed in the face of the casing directly opposite the opening 20, the purpose of which will be presently set forth.

- The key barrel is made in two independent sections 22 and 23, the outer section 22 being supported so as to revolve freely within the part 6, and extending through a circular opening in the latter, while the inner section 23 is supported to revolve freely within the casing 7, and these elements 22 and 23 have a rotatory engagement with each other, as shown at Figure 4, so that they are properly aligned and may be rotated separately or in unison, the latter instance occurring when the proper key is inserted within the key slots 24 and 25 formed respectively in these members 22 and 23.
- 15 The key slot 24 in the barrel 22 is irregularly shaped, so that a plain flat key cannot be inserted therethrough so as to engage the slot 25 which latter is perfectly plain, and in operating the lock a corrugated key 26 is used as is shown at Figure 10, the corrugations in the key being adapted to fit the irregular contour of the key slot 24.
- 20 Extending from the side of the inner key barrel 23 is a lug 27, and the upper edge of the tumbler 12 on the locking slide and upper edge portion 28 of the locking slide 8 are directly opposite this lug, and when the lug is rotated by the key from the position shown at Figure 8 to the position shown at Figure 9 it will force the tumbler downwardly until the gate 14 is opposite the lug, whereby the latter will be positioned against a shoulder 29 which is substantially a continuation of the edge 28, and the tumbler 25 will have then sprung upwardly so that the gate 14 will embrace the lug 27, and thereby offer a resistance against the accidental movement of the lug away from this shoulder.
- 25 The hollow raised portion 6 is a part of the escutcheon plate 4, and it is within this part 6 of the plate that the outer key barrel is journaled, and pivoted at 30 to the part 6 of the plate structure 4 is a hasp 31 which carries projecting from its inner face a hook-shaped keeper 32, the extreme free end of this hasp being bent outwardly so as to form a finger lift 33.
- 30 Pivoted at 34 to the sides of the hasp at a distance below the pivotal point 30 is a draw bar 35 whose upper extremity is bent inwardly to form a hook-like member 36 which is adapted to be engaged with the hook 2 in the plate 1 as will now be explained.
- 35 When the parts are in their unlocked condition, as shown at Figure 3, and it is desired to lock the trunk or other article, the hasp is swung upwardly, and the draw bar 39 is pushed inwardly so as to effect an engagement between the hook members 2 and 36, and the hasp is then forced downwardly and inwardly so as to draw these hook members into close engagement, and cause the keeper 32 to pass through the opening 20 and engage the bolt 19, this engagement of the parts 32 and 19, forcing the bolt upwardly until the member 32 has been finally positioned whereupon the bolt 19 will, by its resiliency, engage within the member 32, and these parts will then be in their normal locking position.

70 When the parts have been brought into locking position, as above described, it will be quite difficult to force the hasp outwardly so as to disengage the keeper 32 and bolt 19, but the means heretofore described and operated by the key causes the lug 27 to be presented as a barrier against any upward movement of the slide 8, while the engagement of the gate 14 in the tumbler 12 with this lug, will render this locked position of the parts quite secure as against accidental displacement.

75 80 It will be noticed that a portion of this lug 27 and one wall of the gate 14 are slightly chamfered, so that when the barrel 23 is operated to unlock the parts these beveled portions will cause the tumbler to yield.

85 It will also be noticed that the contact surfaces of the bolt 19 and keeper 32 are rounded, so that their forced engagement in the manner above described, will cause the yielding of the bolt.

90 95 The opening 21 in the casing has no function except to remove the stock of the casing so that it will not interfere with the keeper when the latter is in locked position, and if the casing were merely indented at this particular location, the invention would be served equally as well.

The key barrels are made to rotate independently, so that any tampering with the outside barrel to rotate the same will not effect the rotation of the inside barrel.

100 105 The corrugated key opening in the outside barrel renders it exceedingly difficult to reach the inside barrel and rotate it.

What is claimed is:—

ber fixed to the trunk lid, a plate structure secured to the trunk body and having an opening in its lower end, a casing secured to the under side of said plate structure, a slide bolt within said casing and positioned 5 immediately opposite said opening, a hasp pivoted at its upper end to said plate structure and having a hook shaped keeper extending from the inner face of its lower end, a draw bar pivotally carried by said hasp and adapted for locking engagement with said hook member, the closing of the hasp causing said bolt to automatically engage within said keeper with the draw bar firmly 10 engaged within said hook structure, independently rotating outer and inner key barrels journaled within the plate structure and casing, said barrels having key slots, the slot in the outer barrel being irregular to accommodate a corrugated key, while the inner barrel has extending laterally therefrom a lug, a spring actuated tumbler pivoted to the slide bolt and formed with a gate in its upper edge, whereby, when the barrels 15 are rotated by the key said lug will force said tumbler downwardly against its resiliency and will abut a part of the slide bolt and will be engaged within said gate by the resilient recovery of the tumbler.

20 30 In testimony whereof I affix my signature hereto.

ALBERT J. KOMENAK.
